POWER CONTROL

Stanley M. Udale, Detroit, Mich., assignor to
George M. Holley and Earl Holley

Application January 31, 1942, Serial No. 429,065

5 Claims. (Cl. 123—98)

The object of this invention is to prevent an engine running away or racing whenever the propeller drops off. When a large engine over 1000 horsepower is operating a propeller, if the propeller breaks the engine races and before the operator of the engine can close the throttle, the engine tears itself loose from its supports and a complete wreck results.

In the manipulation of reverse gears a situation arises on a marine engine when the engine may have no load on it, and if during this period the throttle is opened, serious results occur. In a similar way, in an airplane when the propeller is set to feather so that it offers no resistance to rotation, if the throttle is accidentally opened with the propeller so adjusted and with no load on the engine, again the engine will immediately rotate at a dangerously high rate of speed.

Various centrifugal devices are in use to take care of this situation but they are not reliable. If the ignition is cut off then there is a danger of explosive mixtures getting into the muffler unless the fuel is cut off at the same time as the ignition is cut off. There are various power control devices in general use, but these devices are somewhat complicated and expensive.

Therefore, the object of this invention is to provide a simple power-limiting means which will automatically close the throttle once the engine exceeds the maximum power and will necessitate the complete closure of the throttle before the throttle can be re-opened so that there will be no hunting.

This is an added safety feature because when the throttle is closed, the operator can listen and discover whether any damage occurred when the engine was overstressed during the moment when the automatic device was engaged in closing the throttle. It must be realized that no device will operate instantaneously and therefore even an automatic device will not prevent excessive speed for a second or possibly two seconds. The rate of acceleration of an engine which has no load on it is unbelievably great and no human being can possibly react quickly enough to save the engine, and even a mechanical device does not act any too quickly.

In the drawing, the figure shows diagrammatically the essential features of my invention.

In the figure, 10 is the air entrance to a carburetor of a well known type having a fuel entrance 11 controlled by a needle valve 12 which discharges between the two throttles 13 and 14 which between them constitute a variable venturi.

The two throttles 13 and 14 are connected by a chain of gears operated by the gear 15 which engages with a gear 16 which engages with a gear 17. The gear 16 is mounted on the throttle 14 and the gear 17 is mounted on the throttle 13. A cam 19 engaging with a roller 20 moves the lever 21 which engages with the needle valve 12. The spring 22 maintains the roller 20 in engagement with the cam 19. The needle 12 therefore moves with the throttles 13 and 14 and the cam 19 is arranged to give the correct mixture ratio at every throttle position. The diaphragm chamber 23 which is bounded on the left by the diaphragm 24 is bounded on the right by the diaphragm 25, and these diaphragms form the right and left hand walls of air chambers 26 and 27 and control the fuel inlet valves in a well known manner. The detail whereby the air pressure in the chambers 26 and 27 is controlled is no part 20 of this invention.

Obviously the mixture ratio can be modified by varying the pressure in these chambers as the load and altitude vary. The mixture fuel flowing by the passage 16 goes past the restriction 28 down the passage 29 and issues through 30, 31 in the throat of the variable venturi formed between the two throttles 13 and 14. The mixture then flows through the opening 32 into a supercharger (not shown) enclosed in the housing 33. The pipe 34 transmits the supercharger pressure created in the housing 33 to the chamber 35 which houses the aneroid bellows 36 which is mounted on the wall of the chamber 35. This bellows 36 carries a movable contact 37 which engages with another movable contact 38. An electric wire 39 is connected to the contact 38 and an electric wire 40 is connected to the movable contact 37. As the chamber 35 is a closed chamber obviously the bellows 36, which is a sealed chamber, will move the contact 37 up and down as the pressure of the supercharger varies. The contact 38 is mounted on the spring 41 which is mounted on the cover 42 of the chamber 35. An eccentric adjustment 43 moves the movable contact 38 so that the specific pressure at which the supercharger causes the contacts 37 and 38 to separate can be adjusted closely. Forty-four or forty-five inches of mercury are the common figures between which it is desired to close the throttle.

When the contacts are in contact with each other, current is able to flow through the electric wire 39 to the electric wire 40. The electric wire 40 is connected to a solenoid 44 which is grounded through the connection 45. This sole-

noid 44 is mounted in a cup-shaped receptacle 47 which acts as a magnet in attracting the movable armature 48 against the action of a spring 49.

This spring 49 tends to move the armature 48 away from the cup-shaped receptacle 47. A rod 50 is connected to the broken links 51 and 52 so that when the current is broken and the solenoid 44 is no longer operative to hold the armature 48 against the cup-shaped element 47, the spring 49 pushes the rod 50 upwardly.

Tracing through the gears 15, 16 and 17, it is obvious that once the links 51 and 52 are broken, the throttle-operating lever 53 at any position of the manually controlled throttle lever 54 is closed, that is to say, the lever 53 rotates in a clockwise direction, assuming the lever 54 is stationary, and therefore the throttle 14 rotates in an anti-clockwise direction and the throttle 13 in a clockwise direction. By this means, whatever the position of the throttle lever 54 the throttle will close, and even if the throttle control lever 54 were placed so that the throttles 13 and 14 are wide open, even then the throttles 13 and 14 will close to a point where the engine will not run away, that is to say, the speed will not exceed the safe maximum speed, so that if for any reason the load is suddenly thrown off the engine, the automatic throttle control lever 53 rotates clockwise, the two throttles 13 and 14 close and the engine is held down to some safe maximum revolutions per minute of the engine.

Although the supercharger will then cease to create the pressure at which the contacts 37 and 38 open, the solenoid 44 becomes active, but it is not powerful enough to attract the armature 48 and to compress the spring 49 and therefore the throttles will remain partially closed. If the manually controlled throttle lever 54 is moved clockwise to close the throttles 13 and 14 completely to the idle position, the lever 53 engages with a stop 55 so that the lever 54, when pulled in a clockwise direction, causes the broken links 51 and 52 to straighten out. The rod 50, therefore, is pushed down by this movement of the lever 54 onto the armature 48 and the spring 49 is thus compressed, so that once more the armature is in place and the solenoid again is sufficiently powerful to hold the part 48 in the position shown in the drawing, until an excessive pressure is built up in the chamber 35 once more. Of course, when taking off with a plane it would be necessary to lock the armature 48 in the position shown in the drawing as the safety device cannot be operative under such conditions as a sudden closing of the throttle during the take-off maneuver might cause the plane to crash. However, the device is intended primarily for use when testing the engine before taking off and after the plane is safely in the air to prevent overloading the engine in flight.

A suitable locking device 23 is shown engaging with a guide rod 71 extending upwardly from the armature 48.

Additional protection against an engine running away when the load is thrown off is provided by means for opening the electric circuit and releasing the electromagnet 47 whenever the fuel flow exceeds a predetermined maximum. The reason for this additional protection is that at high altitudes, although the supercharger pressure might not be excessive, excessive power could be developed, especially with mechanically driven superchargers due to the fact that the back pressure falls. A given value for mani-

fold air pressure gives an increasing mean effective pressure at high altitude.

A venturi 56 in the fuel passage 11 will accomplish the same result and replace the more complicated device 34-35-36-37-38-39-40-41-42-43. A pipe 57 communicates the depression in the throat of a venturi 56 to a chamber 58 in which a spring 59 depresses a diaphragm 60 and causes a contact 61 to engage with a contact 62, which contact is connected to the electric wire 39. An arm 63 which carries the contact 61 is connected to another diaphragm 64, which, in its turn, is supported by a spring 67 mounted in a chamber 65 which is connected by a pipe 66 with a diaphragm fuel chamber 68.

An electric wire 69 is connected to the arm 63 and conducts electricity from a battery 70 through the contact 62, 61, through the wire 39, through contacts 37, 38, through the wire 40, through electric magnet 44, to the ground connection 45, so that when either of the two pairs of contacts 38, 37 or 61, 62 are open, the throttle is automatically closed by the breaking of the broken link 51, 52.

The pressure differential created by the fuel flow increases as the square of the revolutions per minute. The presence created by the supercharger 32, 33 also increases as the square of the revolutions per minute of the engine. Hence, when the engine is operated at sea level there is not need of the barometric element 36 and in fact, any other device on the engine which responds to revolutions per minute can be substituted for the supercharger pressure. It follows that a centrifugal governor which opens the contacts 37, 38 would be satisfactory for a marine engine. However, the primary object is to prevent an airplane engine being overstressed and the barometric pressure is a factor in determining the maximum safe speed at any speed. At low altitudes a lower maximum speed will produce excessive power, whereas at high altitudes a higher speed of the engine is needed to produce the same power when the ceiling for the particular supercharger is exceeded. Hence, at low altitudes, the opening of the contacts 37, 38 will protect the engine and the opening of the contacts 61, 62 will protect the engine at higher altitudes. These devices, therefore, can be used together as shown or be used separately.

The broad idea is to break a broken link whenever the power exceeds a predetermined maximum and to compel the operator to close the throttle completely, that is, to the idling position before he can re-open the throttle.

What I claim is:

1. A safety device for an internal combustion engine having an inlet manifold, a throttle valve, a manually controlled lever, a broken link throttle control connected to said lever and to said throttle valve, means for holding said broken link in alignment, means for releasing said holding means responsive to an increase in manifold pressure, means responsive to the movement of said lever to the position of complete closure of said throttle for re-setting the holding means for said broken link to permit the reopening of said throttle by said manually controlled means.

2. A safety device for an internal combustion engine having a throttle valve and a supply of fluid fuel, fuel flow responsive means, a manually controlled lever, a broken link connected to said lever and to said throttle valve, means for holding said broken link in alignment, means for

releasing the holding means responsive to an increase in fuel flow in said flow responsive means above a predetermined minimum flow, and means responsive to the movement of said lever to the position of complete closure of said throttle for re-setting the holding means for said broken link so as to permit the re-opening of said throttle.

3. A safety device for an internal combustion engine having a supercharger, an air entrance thereto, a throttle valve therein, a manually controlled lever, a broken link connected to said lever and to said throttle valve, means for holding said broken link in alignment, means for releasing the holding means responsive to an increase in pressure in said supercharger, means responsive to the movement of said lever to the position for complete closure of said throttle for re-setting the holding means for said broken link to permit the re-opening of said throttle by said manually controlled means.

4. A safety device for an internal combustion engine having a supercharger, an air entrance to

5 said supercharger, a throttle valve therein, a manually controlled lever, a broken link connected to said lever and to said throttle, fuel supply means for said engine, fuel flow responsive means in said fuel supply means, means for holding said broken link in alignment, means for releasing said holding means responsive to an increase in supercharger pressure, additional means for releasing said holding means responsive to an increase in flow in said fuel supply responsive means, means responsive to the movement of said lever to the position for complete closure of said throttle for re-setting the holding means for said broken link to permit the re-opening of said throttle by said manually controlled means.

10 15 20 5. A device as set forth in claim 1 in which the holding means consists of a source of electricity and an electromagnet including an electric solenoid, and the means for releasing said holding means consists of a pair of separable contacts in series with an electric circuit including said electric solenoid.
